UNITED STATES PATENT OFFICE.

STANLEY W. HAYES, OF RICHMOND, INDIANA.

DERAIL.

1,185,663.

Specification of Letters Patent. Patented June 6, 1916.

Application filed October 21, 1914. Serial No. 867,698.

To all whom it may concern:

Be it known that I, STANLEY W. HAYES, a citizen of the United States, residing at Richmond, in the county of Wayne and State of Indiana, have invented the following described Improvements in Derails.

The improvement involves features of construction and relative arrangement of the bearings and other appurtenances to 10 rail construction, tending to improve the smoothness of operation thereof and simplify the process of manufacture, and also providing for the operation of the derail, either manually or from the pipe-line, as 15 may be preferred, as well as certain other features later explained.

In the drawings forming part hereof, Figure 1 is a top plan view of the derail in its open position; Fig. 2, the same in its closed 20 position, showing a part of the standard in longitudinal section and part of the derail block in dotted lines; Fig. 3 is a longitudinal section in the closed position, with the movable derailing member in section; Fig. 4 is 25 a similar view of the open, and locked, derail, with the derailing member thereof shown in elevation; Fig. 5 is a section at line V—V of Fig. 1; Fig. 6, a section on line VI—VI; Fig. 7, a section on line VII—VII; 30 Figs. 8, 9 and 10 are detailed views showing the means for locking the derail in closed position or off the rail; and Figs. 11 and 12 are detail views of derail closed.

The base or standard of the derail is 35 formed, preferably in a single casting, as a base-plate 1 with two opposite flanges 2 depending below it for engagement with the corners of the two adjacent ties, upon which the device is secured by spikes driven 40 through the holes in the main base plate. Above the flanges 2, the base plate is formed with upright portions 3 representing side walls, which are braced by a number of flange ribs 4 and connected at the top by an 45 arch-shaped roof 5, thus forming an enclosure or housing for the body of the moving part of the derail. The base plate 1 is turned upwardly at the end adjacent the rail and the side walls 3 are extended over 50 the upturned part, forming between them a thrust seat for the derailing member, to sustain it against displacement longitudinally of the rail. The end of the base plate or side wall is designed to serve as a gage, to 55 be placed directly against the web of the rail, when spiking the base plate to the ties.

The interior of the standard, except for that portion of it which is immediately adjacent the rail and the thrust-sustaining seat, is open downwardly into the space between the ties, and such interior space accommodates the body part of the moving member, which is guided therein. At the end of the casing, the side walls 3 are turned inwardly forming a relatively narrow rear opening through 60 which the smaller end of the moving member may move. Bearing surfaces for the said member are provided at two points which are relatively remote from each other. Those for the head end of the moving member are provided in the form of two upwardly-curved shelves or ledges 6, forming part of the side wall portions 3, and projecting inwardly no more than necessary to provide an adequate slideway for the derailing member to slide on, and each is curved so that the said member moving or sliding thereon will receive a lifting movement as it advances toward or recedes from the rail. This continuous slideway bearing surface is 65 co-extensive with the stroke of the derail, and does not encroach on the interior space within the casing, which latter is left open, as above stated, so that foreign objects, such as ballast or coal may not be retained therein to interfere with the operation of the device. Any such objects, it will be observed, 70 can pass freely between the shelf bearings 6 over the inclined portion of base plate 1 down into the space between the ties, and 75 since the moving member itself is hollow on its under side, relatively large bodies may thus pass through the standard. The bearing surfaces for the opposite or smaller end of the moving member are formed upon the upper faces of two inwardly projecting lugs 7 on the opposite sides of the opening at the rear end of the standard. These faces are rounded as shown in Fig. 3 and are each disposed directly beneath a corresponding overhanging face 8, also curved. A notch bearing 80 is thus formed on each side of the rear opening to receive the corresponding bearings of the derailing member. The said 85 surfaces are rounded in order to accommodate such tilting of the moving member as may be imparted thereto by the curved shelf bearings above described.

The moving member of the device comprises a derail-block or head 9 adapted to 90 rest upon the head of the rail and deflect passing wheels therefrom, and a body por-

tion which is partially inclosed by the standard. The body portion adjacent the head is about three times the width at the rear or opposite end, and the wider portion 5 is adapted to move or slide within and over the forward part of the standard at the thrust seat, while the narrower portion is adapted to slide back and forth through the small opening in the rear. The body is 10 formed of two side wall portions 10, connected by a roof portion 12 and cross-braced by a number of internal flanges 11, all cast in one piece. The forward ends of the side walls 10 are extended downwardly, forming 15 curved shoulders 13 which are adapted to rest and slide upon the curved shelf bearings 6 on the standard and ride on the latter into the thrust seat between the forward ends of the side walls 3. To facilitate such 20 movement, the side faces of the shoulders 13 are cast with facings 14 on them, which latter are subsequently milled off flat and parallel to the side walls 3, as indicated by the hatching in Fig. 4, thus giving the 25 member smooth, lateral guiding faces. At the rear or opposite end, the side walls 10 of the moving member are provided with outwardly projecting, longitudinally extending flanges 15, adapted to engage, as 30 bearings, in the notches between the curved lug faces 7 and 8 above referred to, such flanges being somewhat longer in length than the throw of the derail, and practically coextensive with the narrow part of the 35 derail member. When the derail-block is upon the rail, as shown in Fig. 4, practically all of the smaller end will be within the standard, whereas in the other position, that end will project in rear of the casing, 40 as shown in the other figures.

With the bearings arranged as above described, the derailing member can move freely and smoothly in either direction, and even in large sizes can be readily manipulated by hand. For this purpose, a hand-hole 16 is provided in the roof 12 of the derailing member near the head, and at a 45 point always in advance of the roof 5 of the standard, so that the operator's hand will be free from contact therewith. In order that the operator may not thrust his hand or fingers too far into the interior of the block, a cross-rib 16^a is formed across the hand-hole, which also serves in some 55 measure to reinforce the derail block and the member as a whole.

The standard roof 5 may normally serve to hold the moving member against upward displacement from its bearing surfaces, but 60 inasmuch as the said roof is required to be relatively short on account of the width of the derail-block and forward part of the body, I prefer to provide special holding-down means, and these consist of two opposite studs 17 projecting from the side walls

10 of the moving member and each disposed beneath an overhanging ledge 18 formed on the inner face of the standard wall. This overhanging ledge, by reason of its location close to the spike flange level, 70 may extend forwardly beyond the roof and for such distance as will prohibit any appreciable upward departure of the derail-block from its prescribed path at any point of its stroke, and, moreover, the said ledge 75 may be curved downwardly at its forward end, as illustrated in the drawings, so as to direct the derail-block into its thrust-sustaining seat, counter to any force tending to lift it. Such directing of the movement 80 is desirable especially when the derail-block is to be thrown by hand, to resist the natural tendency to pull upwardly and without interfering with the opening movement. For connection with a pipe-line or target 85 stand, the rear ends of the flanges 10 are extended downwardly as connection ears and provided with bolt-holes 19, as indicated.

The derail may be locked in either closed 90 or open position, for which purpose a hole 20 is formed in the forward side of the roof or side wall and a projection 21 (Fig. 9) is formed on a corresponding point of the derailing member so that a padlock thrust 95 through the hole will obstruct movement of the derailing member toward the rail. Similarly, a perforated bracket 22 is formed on the rear end of the roof 5 into which the padlock may be inserted so that, the derailing member will be locked upon the rail. Either one or both of these locking means may be employed and in both cases it will be observed that the derail-block will be locked and held against any appreciable 100 movement either away from or toward the rail.

I claim:

1. In a derail, the combination of the movable member having a derailing-head thereon, of a base or standard provided with a bearing for such member engaging the same near the head thereof, a second bearing at the opposite end of said member, and longitudinally extending flanges on said member engaged and guided in the latter bearing. 110

2. In a derail, the combination with the movable member wider at one end than at the other and having a derailing-head at its wider end, of a base or standard forming a bearing for said member, engaging the same beneath said wider portion and provided with opposed notches on opposite sides of the narrower portion of the member, and longitudinal flanges on said narrower portion engaged in the notches. 120

3. In a derail, the combination with the movable member wider at one end than at the other and having a derailing head at the wider end, of a base or standard inclosing 125

5 said wider end and provided with a slide-way bearing therefor, said standard having a rearward opening through which the smaller end of the movable member projects in the closed position, and longitudinal bearing flanges on said smaller portion engaging bearing surfaces in the sides of the rearward opening.

10 4. A derail comprising a moving member having a derailing-head thereon, a base or standard having a forward bearing surface engaging and supporting such member near the head thereof and upon which said member may slide in its movement toward and from the rail, in combination with a second bearing formed in the rear of the standard, and outwardly projecting, longitudinally extending flanges at the opposite end of the movable member engaging the 20 second bearing.

15 5. A derail comprising a moving member having a derailing-head, a base or standard, and bearings for guiding the moving member, comprising inwardly projecting shelf-bearings on the standard adapted to impart a lifting movement to the member guided thereon.

20 6. A derail comprising in combination, a moving member having a derailing-head and a base or standard therefor provided with bearings for guiding the moving member, comprising inwardly projecting ledges on the standard engaging and supporting the member and outwardly projecting flanges on 35 the member engaging the standard.

30 7. In a derail, a derailing member having a derailing-head and a downwardly projecting shoulder thereon adjacent the head, and having also two outwardly projecting bearing flanges on its opposite end, in combination with a base providing a sliding bearing for the said shoulder and a thrust seat to receive the same, and also having notches to receive said bearing flanges.

45 8. A derail comprising a moving member having a derailing-head thereon, a base or standard therefor and a slide-way bearing surface on the standard which supports said member near the head end thereof, longitudinal flanges on the member at its opposite end engaging notches in the standard, and means for confining the derailing member upon such supporting means, comprising a lateral projection on said moving member 50 and a shelf on the standard overhanging the same.

60 9. In a derail, a moving member comprising a derailing-head and a hollow body portion formed of side walls and a connecting roof portion, the side walls of said body portion being extended downwardly and forming bearing shoulders near the derailing-head, and said member having longitudinal flanges on the said side walls at 65 the opposite ends thereof, in combination

70 with a base or standard provided with means engaging and guiding said shoulder and flange portions and coöoperating therewith to impart a lifting component in the movement of the derail.

75 10. In a derail, a base or standard, and a moving member comprising a derailing-head and a body portion formed of side walls and a roof wall joining the side walls and having a hand-hole aperture therein.

80 11. In a derail, a moving member comprising a derailing-head and a body portion formed of side walls and a roof wall joining the side walls and having a hand-hole in the roof wall, the said side walls being extended downwardly as shoulders and provided with outwardly projecting bearing flanges at their opposite ends, in combination with a base or standard having side walls extended toward the web of the rail, 85 a slide-way bearing for the shoulder portions of the derailing member and a thrust-sustaining seat for said portions at the forward end of the base or standard.

90 12. In a derail, a moving member comprising a derailing-member, a standard therefor, a bearing for the moving member adjacent one end thereof comprised of two opposed shelves or ledges upon which said member may slide toward and from the rail, and a rear bearing, and means for confining the member to the rail, comprising a holding-down stud on the member and a separate overhanging ledge on the standard between the bearing surfaces thereof.

95 13. In a derail, the combination with a base or standard having a roof portion, a moving derailing member guided therein and beneath the roof portion, and a padlock-hole in the roof portion adapted to receive a locking member to obstruct movement of the derailing member.

100 14. In a derail, the combination with a sliding derailing member having a projection thereon and a base supporting and guiding such member having a hole therein adapted to receive a padlock and so located as to cause such padlock to obstruct movement of the derailing member on the base without passing through the derailing member.

110 15. In a derail, a base or standard, a derailing member thereon having a hand-hole in its upper portion and means for connection with a pipe line on its lower portion.

115 16. In a derail, a base, a hollow derailing member guided thereon having a derailing head and a hand-hole in the upper wall thereof in rear of the head.

120 17. In a derail, a base, a hollow derailing member having a head, a hand-hole in rear of the head, and a cross flange in the hand-hole adapted to limit the insertion of the operator's hand therein.

125 18. In a derail, a base having a rearward

- opening and a part or bracket adjacent said opening, having a perforation therein adapted to receive a padlock, in combination with a derailing member comprising a body, the rear end of which moves within the opening in the base and is provided with an abutment member adapted to be engaged by the padlock to lock said member against movement within the base.
- 10 19. In a derailing member, a base having a padlock hole in its upper portion, in combination with a derailing member mounted in the base for transverse up and over movement relative to the rail, the said member having an abutment adapted to be blocked against movement by a padlock in said hole.
- 20 20. In a derailing member, a base having side walls connected by a roof and a padlock hole in one of said side walls at the front of the roof, in combination with a de-

railing member mounted in the base for transverse up and over movement relative to the rail and having an abutment adapted to be blocked against movement by a padlock in said hole. 25

21. In a derailing member, the combination of a base having a padlock hole in its upper portion, and a derailing member mounted in the base for transverse up and over movement relative to the rail and having a handhole in its top and an abutment near said handhole to coöperate with a padlock in said hole. 30

In testimony whereof, I have signed this 35 specification in the presence of two witnesses.

STANLEY W. HAYES.
